UNITED STATES PATENT OFFICE

2,656,551

CASEMAKER

Peter Bunch, Chicago, Peter Mittomme, Cicero, and Russell Jennings, Chicago, Ill., assignors to Wilson-Jones Company, Chicago, Ill., a corporation of Massachusetts

Original application October 10, 1946, Serial No. 702,390, now Patent No. 2,596,068, dated May 6, 1952. Divided and this application October 10, 1951, Serial No. 250,678

6 Claims. (Cl. 11-2)

1

This application is a division of our prior application, Serial No. 702,390, filed October 10, 1946, which issued as Patent No. 2,596,068 on May 6, 1952.

This invention relates to a casemaker for applying binding material to a back and a pair of cover boards to form a case or cover for loose leaf binders.

Casmakers have been used in the manufacture of cases for loose leaf binders for many years and have reduced the expense of manufacturing certain types of loose leaf binders considerably because of their tremendous operating speed. However, the efficient use of casemakers was limited to binders having a flat back because no casemaker could bind a case with a rounded binding back in place. Attempts had been made at running a casemaker without a binding back and then inserting a rounded binding back after the case was completed except for the back. These attempts were unsuccessful because the edges of the binding material that cover opposite surfaces of the ends of the binding back in the completed binder were glued together in the casemaker, and the time required to separate these glued edges in order to insert the rounded binding back was so great that the total manufacturing cost for this type of operation was greater than when the cases were made entirely on conventional gluing tables. Attempts have also been made to modify the glue applying mechanism in a casemaker so that area of the rounded binding back do not receive any glue in the casemaker, but these attempts have also been unsuccessful.

It is one object of our invention to provide a casemaker capable of binding a rounded binding back into a case for loose leaf binders. It is a further object of our invention to provide simple means that may be readily applied to a conventional casemaker to adapt it to the manufacture of cases for loose leaf binders having a rounded binding back. Other objects of our invention will become apparent upon reading the following description, taken in conjunction with the accompanying drawings, in which:

Figure 1 is a diagrammatic view of approximately one half a casemaker embodying our invention;

Figure 1A is a view, similar to Figure 1, showing the rest of the casemaker;

Figure 2 is a side elevational view showing the end rollers at one stage of the casemaking operation;

2

Figure 3 is a view, similar to Figure 2, showing the end rollers at a different stage of the casemaking operation;

Figure 4 is a side elevational view showing the portion of the casemaker adapted to press the rounded binding back into position in the case;

Figure 5 is a front elevational view of the structure shown in Figure 4;

Figure 6 is a top plan view of the apparatus for positioning the rounded binding backs in position to be fed to the case, taken along the line VI-VI of Figure 7 so as to show the relative position of the suction holding device;

Figure 7 is a cross sectional view, taken substantially along the line VII-VII of Figure 6, but showing a portion of the structure for feeding the rounded binding back to the case;

Figure 8 is a fragmentary cross sectional view showing the suction holding device and the rollers from which the rounded binding back is fed;

Figure 9 is a longitudinal sectional view taken substantially along the line IX-IX of Figure 6, but showing a portion of the structure for feeding the rounded binding back to the case;

Figure 10 is a cross sectional view taken along the line X-X of Figure 6;

Figure 11 is a cross sectional view taken along the line XI-XI of Figure 9;

Figure 12 is a detail perspective view of the rounded binding back;

Figure 13 is a fragmentary perspective view showing a plurality of cases as they appear in the casemaker, just before and after the rounded binding back is positioned thereon;

Figure 14 is a detail perspective view of a case before the rounded binding back is bound in; and

Figure 15 is a detail perspective view of a completed case, ready for having a ring metal secured thereto.

Much of the apparatus shown diagrammatically in the drawings is conventional and will not be described in detail as it does not constitute any part of the invention. Such structure has to be shown, however, to make it possible to get a general understanding of the entire device so that the specific improvements which are the subject of the present invention may be clearly understood.

Briefly described the casemaker comprises a spindle 2 from which a roll of fabric or other binding material 3 is fed into contact with a glue roller 4 to apply a tacky coating on one surface of the binding material. The binding material, with its tacky surface uppermost, is fed past a

pair of stacks of cover boards 5 and 6. Pneumatically controlled suction devices 7 and 8 each lift one cover board off each stack 5 and 6 and then press them down in predetermined position on the tacky surface of the binding material. After the suction devices 7 and 8 are released and have started on their next cycle the binding material and cover members are fed through a pair of pressure rollers 9 and 10 which adhere the cover boards firmly to the binding material. A shuttle mechanism 11 positioned just beyond the pressure rolls 9 and 10 is moved intermittently by a power driven main shaft 12. The shuttle clamps each board and the binding material and moves them to the right, as seen in Figure 1. When the shuttle reaches the end of its stroke it releases its grip on the board and binding material and moves back to the left to grip the next board. This movement constitutes the feeding movement of the binding material off the spindle 2. Adjacent the shuttle 11 is a corner cutting mechanism 12 the knives of which are synchronized with the shuttle movement so that corners 13 and 14 are cut at opposite sides of the binding material at regular spaced intervals.

After the corners 13 are cut, the fabric and covers are moved to a mechanism for positioning the round binding back 15 on the binding material between the cover boards. The next mechanism rolls the sides of the binding material against the covers. These mechanisms constitute an essential part of our invention and will be hereinafter described in detail.

After the sides of the binding material are rolled down against the cover boards the binding material continues on its movement until it reaches a knife 16, which is also synchronized with the feeding movement of the shuttle 11, and descends at regular intervals to separate the binding material transversely along a line extending from the notch or corner 13 to the opposite notch or corner 14. The ends of the binding material are rolled down against the cover boards by sets of rollers 17 and 18. The rollers are moved vertically and springs 19 and 20, shown better in Figures 2 and 3, pull the rollers against the ends of the binding material. Since the knife 16 has severed the binding material the feeding movement of the shuttle no longer controls the movement of the case. A series of rollers 21 and 22, positively driven from the main shaft 12, feeds the cases from the knife 16 to a chain conveyor 23 which is also driven from the main shaft and is provided with upstanding lugs 24 to push the case along as the chain moves. The knife 16, and rollers 17, 18, feeding rollers 21, 22 and the chain conveyor 23 are all conventional and do not constitute part of the present invention.

The chain conveyor 23 moves the case into contact with a round cornering machine 25. The round cornering machine includes four arms 26, 27, 28 and 29, each adapted to hold down one corner of the case, and four presser arms 30, 31, 32 and 33 which slide towards each corner and fold the binding material around each corner of the case and are then retracted when the unit carrying the arms 26, 27, 28 and 29 is lifted. This portion of the round cornering machine is old, but we have added thereto a transverse pressure bar 34, shown also in Figures 4 and 5, for securing the sides of the binding material 3 over the ends of the rounded binding back 15. When the case is carried from the round cornering machine 25 by the chain conveyor 23 it is finished and is ready to receive a ring metal. The attachment of the

ring metal is a separate, subsequent operation, not connected with the casemaker.

Referring specifically to Figures 6 to 11, inclusive, the means for positioning the rounded binding back on the case includes a chute 35 which is grooved, as indicated at 36 in Figure 11, to conform to the curvature of the rounded binding back. The rounded binding backs are inserted in the chute and are then slid along the chute under flanges 37 and 38. The chute 35 is adjacent to a pair of rollers 39 and 40 provided with longitudinal grooves 41 and 42 in registration with the space between the top edges of the grooves 36 and the underside of the flanges 37, 38 so that the binding backs may be pushed through the chute 35 and the edges of each will engage in the grooves 41, 42 in succession. The grooves are provided with overhanging flanges 43, 44 at the entering end to prevent the binding backs from being pushed out of the chute 35 into engagement with the rollers 39 and 40 when the grooves 41 and 42 are not in proper registration with the chute. The grooves 41 and 42 are moved out of registration with the chute 35 only for a very short interval of time when rollers 39 and 40 are rotated downwardly by the downward movement of the binding back 15 towards the binding material 3. One of the rollers 39 has a collar 45 secured thereto to stop the sliding movement of each binding back in proper position. The succeeding binding back is not pushed into contact with the collar 45 until after the suction cup assembly, hereinafter described, moves up to clear the space between grooves 41 and 42.

The rollers 39 and 40 are rotatably mounted in brackets 46 and 47 which are secured to the bed 48 of the casemaker. Each roller 39, 40 has a wheel 49, 50 mounted thereon, as shown in Figure 10. A pin 51, 52 projects laterally from each wheel and the ends of the pins rest on fixed supports 53, 54 when the rollers are positioned with the grooves 41, 42 ready to receive the edges of a rounded binding back. A tension spring 55, 56 is secured at one end to the pin 51, 52, and at its other end to the base plate 57 which is secured to the bed 48. As each binding back is moved downwardly from the rollers 39, 40 to the binding material, in a manner hereinafter more fully described, the rotation of the rollers to release the edges of the binding back from the grooves 41, 42 causes the pins 51, 52 to move upwardly from the supports 53, 54 against the action of the springs 55, 56 as long as positive rotation of the rollers 39, 40 continues. Since this positive rotation is caused by the engagement of the edges 55 of the binding back with the grooves it will stop as soon as the edges of the binding back are free of the grooves. The springs 55, 56 will then bring the pins 51, 52 back to their position of rest on the supports 53, 54 and the rollers 39, 40 will have their grooves 41, 42 positioned to receive the next binding back.

The apparatus for feeding the binding back 13 from the rollers 39 includes a suction cup assembly 58 which comprises a plurality of suction cups 59, a housing 60, a stem 61 and a flexible suction hose 62. As may be seen in Figure 1, the flexible suction hose is connected to a valve housing 63. A valve control 64 projecting from one wall of the housing engages a cam 65 mounted on the main drive shaft 12 and is controlled thereby. This control is synchronized with the vertical movement of the suction cup assembly so that as the assembly moves downwardly the suction is on and the binding back is held firmly against the suction cups. This prevents the binding back

from falling after it is released from the grooves 41, 42, and insures proper positioning of the back on the binding material. When the binding back is initially secured to the binding material the suction is automatically turned off by the valve control 64 as influenced by the position of the cam 65 at that instant, and the suction cup assembly may be moved back to its uppermost position without displacing the binding back 15 from its proper position on the binding material.

The vertical movement of the suction cup assembly is controlled by a cam 66 (Figure 1) also mounted on the main drive shaft 12'. The cam governs the action of a rocker arm 67 by means of a pin 68 which projects laterally from one end of the rocker arm and rides over the cam. The other end of the rocker arm is pivotally secured to a link 69, as indicated at 70. The upper end of the link 69 is pivotally secured to a cross arm 71, as indicated at 72. The cross arm is pivoted at 73 (Figure 9) to an upright 74 secured to the bed 48. A cross bar 75 extends laterally from the middle of the upright 74 and is rigidly secured thereto in any suitable manner. The free end of the cross bar 75 has a vertical guide 76 rigidly secured thereto.

A vertically depending arm 77 has a pin 78 projecting laterally to engage a slot 79 in the end of the cross arm 71 so that the depending arm 77 will move vertically with the pivotal movement of the cross arm 71. A tension spring 80 has one end secured to the cross arm 71 and its other end to the cross bar 75, as indicated at 81 and 82, respectively, to pull the right hand portion (as viewed in Figure 9) of the cross arm 71, and the depending arm 77, down immediately after the cam 66, acting through the rocker arm 67 and link 69, has pulled the arm 77 up. It will be seen from Figure 1 that as soon as the arm 77 is raised the high section of the cam moves out of contact with the pin 68 and there is nothing to interfere with the action of the spring 80. The depending arm 77 fits within the channels 83, 84 on the vertical guide 76 and its vertical movement is guided thereby. A clamp 85 is rigidly secured to the arm 77 and moves therewith. The clamp is secured also to the stem 61 of the suction cup assembly so the suction cups move up and down with the arm 77.

As the binding material 3 moves into position to receive the rounded binding back 15 guide members 86 turn the ends of the binding up so that they are substantially vertical when the binding material reaches the next station. The feeding movement of the binding material is intermittent, as governed by the reciprocating movement of the shuttle mechanism 11, and, as the binding material comes to rest, a pair of holding members 87 move down against the cover boards to hold them in position while side rollers 88 move inwardly over both edges of the binding material to adhere them to the cover boards. The holding members 87 are cut out, as indicated at 89, to provide clearance for the rounded binding back 15. The rollers 88 are also recessed or cut away, as indicated at 90, to provide clearance for the rounded binding back.

When the case is positioned in the round cornering machine 25 for the round cornering operation the sides of the binding material are pressed into contact with the ends of the rounded binding back by means of a presser arm 91 secured to the undersurface of the block 92 which constitutes part of the round cornering mechanism and reciprocates vertically relative to the bed 48 upon

which the case rests. As shown best in Figures 4 and 5, the presser arm 91 comprises a cross piece 93 secured to the block 92 and having blocks 94 secured at its ends. This leaves the center portion clear so that the presser arm may be used with binding backs that have prongs projecting therefrom for the attachment, at a later operation, of a ring metal. The presser arm could be made of a solid block of wood, but we prefer the structure illustrated because it may be used with any type of binding back. The lower surfaces of the blocks 94 are curved, as indicated at 95, to conform to the curvature of the binding back so that the binding material is pressed smoothly against the binding back.

From the foregoing it will be seen that we have modified a conventional casemaker to adapt it for making cases for loose leaf binders having rounded binding backs. While we have described a preferred embodiment of our new structure in considerable detail, it will be understood that the description thereof is intended to be illustrative, rather than restrictive, as many details may be modified or changed without departing from the spirit or scope of our invention. Accordingly, we do not desire to be limited to the exact structure described, except as limited by the appended claims.

We claim:

1. In a casemaker, a flat bed for supporting a sheet of binding material, means for positioning a pair of cover members and a rounded binding back on a sheet of binding material, means for adhering the side edges of said binding material to said cover members, said last mentioned means being provided with a clearance space adjacent said rounded binding back to prevent said last mentioned means from contacting the portions of binding material adjacent said rounded binding back, and separate presser means for adhering the portions of said binding material adjacent said rounded binding back to said rounded binding back after said side edges of said binding material have been adhered to said cover members.
2. In a casemaker, a flat bed for supporting a sheet of binding material, means for positioning a pair of cover members and a rounded binding back on a sheet of binding material, laterally movable means for adhering the edges of said binding material adjacent said covers to said covers, and separate vertically movable presser means for adhering the edges of said binding material adjacent the ends of said binding back to said back.
3. In a casemaker, a flat bed for supporting a sheet of binding material, means for positioning a pair of covers and a rounded binding back on a sheet of binding material, means for adhering the corners of said binding material to the corners of said covers, a presser bar secured to said last mentioned means, said presser bar carrying blocks provided with a rounded bottom surface adapted to fit in said rounded binding back to adhere portions of the edges of said binding material to the ends of said rounded binding backs.
4. In a casemaker, a flat bed for supporting a sheet of binding material, means for positioning a pair of cover members on a sheet of binding material in spaced relationship to each other, a pair of rollers grooved longitudinally to hold the edges of a binding back, vertically movable means for moving said binding back from said grooved rollers and positioning it on said binding material between said cover members, means for adhering the edges of said binding material adja-

cent said covers to said covers, and separate means for adhering the edges of said binding material adjacent the ends of said binding back to said back.

5. In a casemaker, a flat bed for supporting a sheet of binding material, means for positioning a pair of cover members on a sheet of binding material in spaced relationship, means for positioning a rounded binding back on said binding material between said cover members, roller 10 means for folding the edges of said binding material over the edges of the covers and the adjacent ends of said binding back, said roller means having pressure surfaces divided to engage the binding material adjacent each cover to adhere it thereto without engaging the binding material adjacent the end of the binding back interposed between said covers, a presser bar, a block secured to the underside of said presser bar, said block being rounded on its lower surface to conform 20 to the contour of the rounded binding back, and means to move said presser bar vertically to force said block against the binding material folded over the ends of the binding back to adhere it thereto.

5

10

25

6. In a casemaker, a flat bed for supporting a sheet of binding material, means for positioning a pair of cover members on a sheet of binding material in spaced relationship to each other, a pair of rollers grooved longitudinally to hold the edges of a binding back, suction means engageable with the top surface of a binding back and movable downwardly between said rollers for moving said binding back from said grooved rollers and positioning it on said binding material between said cover members, means for adhering the edges of said binding material adjacent said covers to said covers, and separate means for adhering the edges of said binding material adjacent the ends of said binding back to said back.
